(Continued)*Primary Examiner* — Selina Sikder*(74) Attorney, Agent, or Firm* — Faegre Drinker Biddle & Reath LLP(57) **CLAIM**

The ornamental design for a light-emitting element module as shown and described.

DESCRIPTION

FIG. 1 is a front view of a light-emitting element module of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top and left side perspective view thereof; and,

FIG. 8 is a rear, bottom and left side perspective view thereof.

The broken lines show portions of a light-emitting element module that form no part of the claimed design.
